UNITED STATES PATENT OFFICE.

LUCIUS S. BIGELOW, OF HARRISBURG, PENNSYLVANIA.

PAPER-RULING MACHINE.

SPECIFICATION forming part of Letters Patent No. 445,518, dated January 27, 1891.

Application filed May 21, 1890. Serial No. 352,631. (No model.)

To all whom it may concern:

Be it known that I, LUCIUS S. BIGELOW, a citizen of the United States, residing at Harrisburg, in the county of Dauphin and State 5 of Pennsylvania, have invented certain new and useful Improvements in Paper-Ruling Machines, of which the following is a specification, reference being had therein to the accompanying drawings.

10 This invention relates to certain new and useful improvements in paper-ruling machines, the peculiarities of which will be hereinafter described and set forth.

In the accompanying drawings, forming a 15 part of this specification, and on which like reference-letters indicate corresponding parts. Figure 1 represents a side elevation of a ruling-machine of the ordinary or any approved type; Fig. 2, a plan view of a portion of the 20 machine, showing my improvements applied thereto; and Fig. 3, a rear view of a portion of the machine, showing the driving mechanism.

The letter A designates the frame of the ordinary or any approved type, upon which the 25 mechanism of a ruling-machine is mounted.

The letter B designates a power-pulley loosely mounted upon a shaft C, secured to the frame. On this shaft I also mount a 30 driving-pulley D and a driving gear-wheel E. A sliding clutch composed of a collar G and prongs H and I is mounted on this shaft, and connected with an actuating-rod J, controlled by a hand-lever K. These instrumentalities 35 form the subject-matter of an application filed by me, of even date herewith, for improvements in paper-ruling machines. Either this type of driving mechanism or some other form may be used as constituting this element of my improved organization. The 40 gear-wheel E meshes with the gear-wheel L, carried by the upper feed-roller O, and through L it meshes with the gear-wheel M, carried by the lower feed-roller P, by which the paper is 45 fed into the machine in the ordinary manner.

An idler gear-wheel Q connects the gear-wheel M with a pinion R on the shaft of the pen-cylinder S. Here motion is applied to the power-pulley, and it is in this manner 50 transmitted to and through these several rollers.

The letter T designates a roller about which is passed one end of the lower apron, and the letter U another roller against which one part of the apron works, (and which performs 55 other functions unnecessary to be described in connection with this invention.) The arbor of the roller U carries the pulley V, which is belted by means of a cross-belt W with the driving-pulley D. When the particular type 60 of driving mechanism shown is used, the feed-rollers and pen-cylinder and their immediately co-operating parts are revolved, together with the rollers T and U and their immediately co-operating parts; or the latter and 65 their parts may be operated independently of the former and their parts. This is more fully set forth in the application above referred to. It is accomplished by engaging and disengaging the prongs I with and from 70 the gear-wheel E. A portion of the lower apron is shown at X. A shaft a, preferably mounted on the rear upper corner of the machine, carries a belt-wheel b and a belt-pulley c, the latter of comparatively small diameter. 75 The shaft d, also mounted upon the frame, and preferably at the lower middle portion and at one side carries a belt-wheel e and a belt-pulley f, the latter being also of relatively small diameter. 80

At g is represented an electrical motor of any approved style, the same being secured to the frame of the machine or floor and having a fixed relation with the speed-reducing pulleys which enter into the organization of 85 the driving mechanism. For the sake of clearness those pulleys which are immediately connected with the operating parts of the machine are termed the "driving mechanism," and the other parts of the driving 90 mechanism are called "speed-reducing pulleys," which are meditately connected with the operating parts and immediately connected with the driving mechanism proper.

The motor has a pulley h, belted by a belt 95 i with the belt-wheel b. The relative size of this wheel and pulley reduces the speed of the pulley c, which is connected with the wheel b. This reduced motion is transmitted to the belt-wheel e by a belt j. A third belt 100 k serves to communicate motion from the belt-pulley f, connected with the wheel e and

developing less speed, to the driving-pulley B, already referred to. It will now be seen that the organization presented admits of the use of a high-speed motor in a machine of this character, where the operative parts are driven comparatively very slowly. The speed-reducing pulleys forming a part of the organization of the driving mechanism and being a part of the equipment of the machine in 5 regard to the construction of this part of its machinery make the machine complete when it leaves the factory for operation by a high-speed motor. Some other kind of high-speed motor, as a water motor, might be used; but the electrical motor is preferred. I have 10 illustrated and described four speed-reducing wheels and pulleys. A smaller or a greater number might be employed and organized with the remainder of the driving mechanism; but this is a convenient number.

It will be observed that the machine as thus organized is equipped in regard to a peculiar kind of driving mechanism—to wit, a driving mechanism with speed-reducing pulleys or 15 wheels. The motor is preferably secured to the machine so that the machine is equipped in regard to the motor also. The sizes of the pulleys or wheels are to be determined by the proper speed to be transmitted to the several operative parts of the machine and with 20 relation to the average velocity of high-speed motors.

On the shaft of the cylinder S are usually carried the cams for operating the pen-beam. In some cases, however, such cylinder and cams are dispensed with. In these cases the pen-cylinder and cams will not enter into the organization of the machine, and I therefore claim my improved speed-reducing mechanism whether used with or without such 25 cylinder and cams.

Having thus fully described my invention, what I claim as new, and desire to secure by Letters Patent, is—

The combination, with the frame of a ruling-machine and a high-speed motor mounted adjacent thereto, of a pen-cylinder and lower feed-rolls mounted on said frame, a power-pulley B and a shaft therefor on said frame, a driving-pulley D, belted to the said lower feed-rolls, a driving-gear E, geared to said pen-cylinder through speed-conveying gearing, a 30 clutching device connecting the said pulley D and gear E and adapted to clutch with and unclutch from the said pulley B, and speed-reducing pulleys mounted on said frame and 35 belted together to the pulley B and to said motor.

In testimony whereof I affix my signature in presence of two witnesses.

LUCIUS S. BIGELOW.
